US0D1050168S

(12) **United States Design Patent** (10) Patent No.: US D1,050,168 S
Riffault et al. (45) Date of Patent: ** Nov. 5, 2024

- (54) **DISPLAY SCREEN OR PORTION THEREOF WITH GRAPHICAL USER INTERFACE**

(71) Applicant: **Datadog, Inc.**, New York, NY (US)

(72) Inventors: **Ludovic André Bernard Riffault**, Montrouge (FR); **Kemper Bauder Smith**, Madison, WI (US); **Omar Waleed Nema**, New York, NY (US); **Pierre Alain Joseph Cariou**, Paris (FR); **Tarek Helmy Sherif**, New York, NY (US)

(73) Assignee: **Datadog, Inc.**, New York, NY (US)

(**) Term: **15 Years**

(21) Appl. No.: **29/953,706**

(22) Filed: **Jul. 23, 2024**

(51) **LOC (14) Cl.** 14-0

(52) **U.S. Cl.**
USPC **D14/48**

CLAIM

The ornamental design for a display screen or portion thereof with graphical user interface, as shown and described.

DESCRIPTION

The FIGURE is a front view of a display screen or portion thereof with graphical user interface, showing our new design.

The outermost broken line of the FIGURE illustrates a display screen or a portion thereof that forms no part of the claimed design.

The remaining broken lines illustrate portions of the graphical user interface that form no part of the claimed design.

1 Claim, 1 Drawing Sheet
